UNITED STATES PATENT OFFICE.

CHARLES CHEERS WAKEFIELD, OF LONDON, ENGLAND.

LUBRICATING SYSTEM AND APPLIANCE.

1,198,173.

Specification of Letters Patent. Patented Sept. 12, 1916.

Application filed February 24, 1916. Serial No. 80,242.

To all whom it may concern:

Be it known that I, CHARLES CHEERS WAKEFIELD, a subject of the King of England, residing in London, England, have invented certain new and useful Improvements in Lubricating Systems and Appliances, of which the following is a specification.

This invention is for improvements in or relating to lubricating systems and appliances and has for one of its objects to provide a device which may be readily applied to existing force-feed or mechanical lubricating systems and whereby steam is admixed with the lubricating oil before it is delivered to the parts to be lubricated.

For convenience the device to which this invention specifically refers will be termed in the following description a "steam and lubricant mixer" and the main body of the device will be referred to as the "steam-distributing box".

It is well-known to mix steam with the lubricant for lubricating those parts to which steam for working purposes is supplied, and the lubricant for this purpose has either been passed into the live-steam pipe or into a mixing-chamber where it mixes with the steam prior to being fed therewith to the part to be lubricated. The present invention therefore has reference to a specific construction of steam-distributing box and consists in the combination with a steam-distributing box having a longitudinal steamway, transverse lubricant-passages in a different plane from that of the steam-way, mixing-chambers which communicate each with a different transverse passage and also through steam feed passages, one for each mixing-chamber, with the steam-way, of means for connecting a plurality of lubricant conduits to the box, each in communication with the free end of a different transverse passage, and means for connecting a plurality of delivery-conduits to the box each in communication with a different mixing-chamber for the purpose of providing a simple fitting for which only one steam-connection is necessary for any number of lubricating conduits.

In the accompanying drawings which illustrate one method of carrying out this invention:—Figure 1 is a plan of the steam and lubricant mixer; Fig. 2 is a vertical section through the device on the line 2—2

of Fig. 1, and Fig. 3 is a vertical section through the device on the line 3—3 of Fig. 1.

The same letters indicate the same parts throughout the drawings.

The distributing-box A is oblong in form and may be cast in a single piece. It has a longitudinal steam-way A¹ which is conveniently drilled from one end of the box which is afterward plugged as at A². At the top of the box a projection A³ is provided which is screw-threaded to receive connections for a steam-supply pipe A⁴.

Above the steamway A¹ is a series of transverse lubricant-passages B and screwed into one side of the box opposite each of such passages is a fitting B¹ having a screw-threaded end B² which receives connections for a lubricant-supply conduit B³. The fitting B¹ containing a check-valve B⁴ forms no part of the present invention and therefore need not be described in the specification. Each passage B has free communication with the fitting B¹ opposite it, so that the lubricant fed in by each supply-conduit B³ can pass to the said passages B through the respective check-valves B⁴.

On the opposite side of the distributing-box is a series of projections C in which mixing-chambers C¹ are formed. These projections are internally screw-threaded to receive a baffle-piece C² which is in the form of a plug reduced in diameter at its center. The baffle-piece is drilled longitudinally from one end into the reduced central portion to provide a passage c and from the end of this passage it is drilled transversely at c¹, which transverse passage opens out at both ends at the sides of the reduced central portion of the baffle so that there is communication again at this point with the mixing-chamber C¹. The reduced portion of the plug or baffle is provided with another transverse passage c³ near the passage c¹ but preferably at right-angles thereto, and from this passage c³ a second longitudinal passage c⁴ extends to the end of the plug opposite that at which the passage c¹ is provided. The passages c to c⁴ are all of a restricted character.

The outer end of each projection C is screw-threaded to receive connections for a lubricant-delivery conduit C⁵.

Screwed into the bottom of the distributing-box A is a plurality of plugs D one of which is situated beneath each of the trans-

verse passages B. Above each plug and above the steamway A¹ is a chamber D¹. In this chamber a ball-valve D² is mounted, which valve is retained in place by a screw-ring D³, said ring providing a valve-seat for the ball. The valve operates to prevent fluid from passing through the ring to the steamway A¹. Each chamber D¹ communicates by a restricted steam-feed passage D⁴ with the mixing-chamber wherewith the transverse passage immediately above said chamber D¹ communicates. It will be seen that the screw plugs D are provided to close the outer ends of the borings, which are made for the purpose of forming the chambers D¹ and assembling the parts therein. This distributing-box may be connected to any form of force-feed lubricator and each conduit B³ represents one of the delivery-conduits of such force-feed lubricator. Similarly any one of the conduits C³ may be connected to any part to be lubricated in the same way as the conduits B³ would be connected if the distributing-box were not interposed, or instead of the feed-conduits B³, the distributing-box may in some cases be built on to the force-feed lubricator so that the check-valve fittings B¹ and the lubricator are directly connected, that is to say, without any intermediate conduit. The steam-conduit A⁴ is connected direct to the boiler so that steam pressure is maintained in the steamway A¹ even if the steam-supply for driving the apparatus to which the lubricator is applied is shut off.

The operation of this device is as follows:—Lubricant is constantly fed by the pumps or other devices supplying the conduits B³ past the check-valves B⁴ and through the passages B into the mixing-chamber C¹. Steam also continuously passes from the steam-way A¹ past the valves D² and through the restricted passages D⁴ into the mixing-chambers. Here the steam and lubricant are mixed, which mixing is further aided by the baffle C². The restricted passages through this baffle necessitate an intimate contact between the steam and oil and the steam and oil being released into the mixing chamber C¹ again by the transverse passage c¹ in the baffle, furthers the mixing. The steam and oil thus thoroughly mixed are finally fed into the delivery-conduits C³ and conveyed by them to the parts to be lubricated. The valves D² are important as they prevent lubricant from being discharged into the steamway if any one delivery-conduit C³ should become blocked.

What I claim as my invention and desire to secure by Letters Patent is:—

1. In a steam and lubricant mixer for a force-feed lubricator, the combination with a steam distributing-box having a longitudinal steamway (A¹) transverse lubricant-passages (B) in a different plane from that

of the steamway, and mixing-chambers (C¹) which communicate each with a different transverse passage and also each with a steam-feed passage (D⁴) one for each mixing-chamber, of means for connecting a plurality of lubricant-conduits to the box each in communication with the free end of a different transverse passage, and means for connecting a plurality of delivery-conduits to the box each in communication with a different mixing-chamber, substantially as set forth.

2. In a steam and lubricant mixer for a force-feed lubricator, the combination with a steam-distributing box having a longitudinal steamway (A¹) transverse lubricant-passages (B) in a different plane from that of the steamway, and mixing-chambers (C¹) which communicate each with a different transverse passage and also each with a steam-feed passage (D⁴) one for each mixing-chamber, of means for connecting a plurality of lubricant-conduits to the box each in communication with the free end of a different transverse passage, means for connecting a plurality of delivery-conduits to the box each in communication with a different mixing-chamber and a plurality of non-return valves situated operatively, one between each of the aforesaid steam-feed passages (D⁴) and the steamway (A¹) said valve operating to prevent the passage of fluid into the steamway from the mixing-chamber, substantially as set forth.

3. In a steam and lubricant mixer for a force-feed lubricator, the combination with a steam-distributing box having a longitudinal steamway (A¹) transverse lubricant-passages (B) in a different plane from that of the steamway, and mixing-chambers (C¹) which communicate each with a different transverse passage and also each with a steam-feed passage (D⁴) one for each mixing-chamber, of means for connecting a plurality of lubricant-conduits to the box each in communication with the free end of a different transverse passage, means for connecting a plurality of delivery-conduits to the box each in communication with a different mixing-chamber, and a plurality of valves (D²) mounted in chambers (D¹) one adjacent to each transverse passage (B) and above the steamway (A¹) each chamber being in communication with the steamway (A¹) through its valve and having free communication each with one of the steam-feed passages (D⁴) the valves closing against passage of fluid to the steamway, a screw-ring (D³) in each chamber for retaining the valve therein, said ring being situated above the steamway (A¹) and providing a seating for the valve, and screw-plugs (D) in the bottom of the distributing-box for closing the outer ends of borings made for the purpose of forming the chambers (D¹) and admit-

ting the screw-rings (D³), substantially as set forth.

4. In a steam and lubricant mixer for a force-feed lubricator, a steam-distributing box having a longitudinal steamway (A¹), a plurality of lubricant-passages (B) which lie across the steamway but do not intersect the same, screw-threaded means provided along one side of the box for receiving lubricant-conduits the axis of flow through the said means being transverse to that of the steamway (A¹), one such screw-threaded receiving means being located opposite and communicating with the open end of each transverse passage (B), a plurality of mixing-chambers (C¹) situated one at that end of each lubricant-passage remote from the aforesaid connecting means and formed each in a separate lateral projection wherewith the steam-distributing box is provided on the side opposite that to which the lubricant conduits are connected, a plurality of valves (D²) mounted in chambers (D¹) one adjacent to each transverse passage and situated between one of the aforesaid mixing-chambers and its corresponding means for connecting a conduit to the passage (B) which feeds it, each valve-chamber being in communication with the steamway (A¹) through its valve, the said valve being arranged to close against the passage of fluid to the steamway, a plurality of steam-feed passages one connecting each mixing-chamber with its corresponding valve-chamber, a screw-ring (D³) in each valve-chamber for retaining the valve therein, said ring being situated above the steamway (A¹) and providing a seating for the valve, screw-plugs (D) in the bottom of the distributing-box for closing the outer ends of the borings made for the purpose of forming the chambers (D¹), and means for connecting a plurality of delivery conduits to the box each in communication with a different mixing-chamber, substantially as set forth.
5. In a steam and lubricant mixer for a force-feed lubricator, a steam-distributing box having a longitudinal steamway (A¹), a plurality of lubricant-passages (B) which lie across the steamway but do not intersect the same, screw-threaded means provided along one side of the box for receiving lubricant-conduits the axis of flow through the said means being transverse to that of the steamway (A¹), one such screw-threaded receiving means being located opposite and communicating with the open end of each transverse passage (B), a plurality of mixing-chambers (C¹) situated one at that end of each lubricant-passage remote from the aforesaid connecting means and formed each in a separate lateral projection wherewith the steam-distributing box is provided on the side opposite that to which the lubricant conduits are connected, a plurality of valves (D²) mounted in chambers (D¹) one adjacent to each transverse passage and situated between one of the aforesaid mixing-chambers and its corresponding means for connecting a conduit to the passage (B) which feeds it, each valve-chamber being in communication with the steamway (A¹) through its valve, the said valve being arranged to close against the passage of fluid to the steamway, a plurality of steam-feed passages one connecting each mixing-chamber with its corresponding valve-chamber, a screw-ring (D³) in each valve-chamber for retaining the valve therein, said ring being situated above the steamway (A¹) and providing a seating for the valve, screw-plugs (D) in the bottom of the distributing-box for closing the outer ends of the borings made for the purpose of forming the chambers (D¹), and means for connecting a plurality of delivery conduits to the box each in communication with a different mixing-chamber, substantially as set forth.

In testimony whereof I have signed my name to this specification in the presence of two subscribing witnesses.

CHARLES CHEERS WAKEFIELD.
